CURTAIN

Maurice Druck, Long Beach, N. Y.

Application April 27, 1945, Serial No. 590,554

2 Claims. (Cl. 160—330)

1

This invention relates generally to window curtains and more particularly to window curtain constructions in which the window covering panel and the valance or edge decoration element together with the supporting and rod carrying portion are combined in a novel and highly useful manner, and methods of making the same.

In the use of curtains for the restriction of vision or reduction of the passage of light through windows or similar building openings it has been known to associate with the main curtain panel, a valance which forms an auxiliary to the main curtain panel and increases the decorative effect of the entire window ensemble. In order to properly support the main curtain panel and the valance, a rod tunnel construction is most frequently used and this has necessitated a plurality of rods and rod carrying structure. Furthermore since the window coverings are subject to considerable dust and dirt, frequent cleaning is necessary and this required the dismounting of separate rods, separate cleaning of the valance and curtain panel, separate insertion and threading of the rods and the reconnection of the rods to appropriate brackets.

It is among the objects of the present invention to provide curtain structure wherein the main or body panel of the curtain and the valance are integral or integrated so that the panel and valance may be simultaneously supported by a single rod.

Another object herein lies in the provision of curtain structure wherein the valance and curtain panel may be laundered, cleaned, stretched, formed, and/or dried as a single unit.

A feature of the present invention lies in the fact that curtains constructed in accordance therewith are hung by a single rod or similar supporting member and yet as hung produce an aesthetically pleasing appearance and to a large extent create the effect of separately hung curtain components.

Another object herein lies in the provision of curtain structure wherein a desirable finished heading effect is obtained with minimum amount of material and labor so that the same may be produced on a large scale with a consequent wide use and distribution.

These objects and other incidental ends and advantages will more fully appear in the progress of this disclosure and be pointed out in the appended claims.

In the drawings in which similar reference characters designate corresponding parts throughout the several views:

2

Figure 1 is a front elevational view showing a first embodiment of the invention.

Figure 2 is an enlarged fragmentary vertical sectional view as seen from the plane 2—2 on Figure 1.

Figure 3 is an enlarged fragmentary vertical sectional view comparable to Figure 2 but showing an alternate form of construction.

Figure 4 is a fragmentary vertical sectional view comparable generally to Figure 2 but showing a second embodiment of the invention.

Figure 5 is a fragmentary end elevational view of the curtain structure shown in Figure 4 during one stage in the fabrication thereof.

Figure 6 is a fragmentary sectional view comparable generally to Figure 2 but showing a third embodiment of the invention.

In the drawings the sectional and end elevational views have the parts exaggerated in thickness for the purpose of clarity in the disclosure, since it will be readily understood to those skilled in the art to which the present invention relates that the curtains described herein may be composed of any desirable fabric or similar material.

Turning now to the first embodiment of the invention illustrated in Figures 1 and 2, the separate curtains generally indicated by numerals 10 and 11 are composed of any suitable planar material preferably of a flexible nature. Since the two curtains 10 and 11 are of substantially identical construction the detailed description of one will suffice for both, it being understood that any desired number of curtains may be hung laterally adjacent to each other on a rod.

As best seen in Figure 2 the curtain 10 includes a body panel 12, a valance 13, a rod carrying tunnel or passage 14, and a heading 15. The rod carrying passage 14 is adapted to be penetrated by a suitable curtain rod such as the rod 16 in a well-known manner.

In accordance with one of the herein described methods the curtain 10 may be formed by taking a piece of material and folding it upon itself through substantially 180° (counter clockwise as viewed in Figure 2) to form the bight 18. The piece of material is then folded upon itself in an opposite direction (clockwise as viewed in Figure 2) through substantially 180° to form the bight or valance lower edge fold 19. The piece of material forming the curtain is then folded upon itself (clockwise as viewed in Figure 2) through substantially 180° to form the bight or heading upper edge fold 20. From this point downward the material is placed so that the upper edge

21 thereof is in juxtaposition and lies rearwardly of the bight 18.

The parts in the positions as described may be secured by the upper row of stitches 22 and the lower row of stitches 23. The upper row of stitches 22 joins the portions 24 and 25 of the material 9 of which the curtain is composed. The lower row of stitches 23 interconnects the portion 27 adjacent the edge 21 to the portion 26, and with the bight 18 there between.

Thus the stitches 22 secure the bottom portion of the heading 15 and the stitches 22 define the upper limit of the rod carrying passage 14. The lower row of stitches 23 secures the upper portion of the valance 13 and fixes it with respect to the body 12, and said stitches hold the bight 18 in position which forms a lowermost portion of the passage 14.

As may be seen from a perusal of Figure 1 where the fabric 9 has a front surface 30 and a rear surface 40 the front surface 30 forms the entire exposed upper part of the curtain. This feature of the invention is particularly valuable where the curtain is composed of materials provided with a surface decoration or treatment on only one surface thereof. Examples of such materials are: pyroxylin coated fabrics; chintzes; tufted fabrics; flocked fabrics; printed fabrics; and the like.

The portion of the rear or "wrong" side of the fabric when the curtain is hung would then lie facing the window or building portions surrounding the same. By the herein described construction both the valance, heading and rod carrying passage are all formed from a single piece of material and are properly disposed and correlated on the finished unitary curtain. Only two rows of stitches are necessary to provide these parts in proper organization and arrangement.

In accordance with the alternate form of the first embodiment of the invention shown in Figure 3, for the purpose of avoiding needless repetition, parts corresponding to the first embodiment are given the same reference characters with the addition of the numeral "1" as a prefix.

From an examination of Figure 3 it will be seen that the upper edge 121 of the material 109 is disposed rearwardly of the portion 126 and forwardly of the bight 118. The portion 127 adjacent the edge 121 is thus sandwiched between the portion 126 and the bight 118, and is maintained in this interposition by the lower row of stitches 123.

This construction produces a desirable finished effect since there are no exposed raw edges, the edge 121 being completely enclosed within the valance 113.

Turning now to the second embodiment of the invention illustrated in Figures 4 and 5 here again for the purpose of avoiding needless repetition parts corresponding to the first embodiment are given the same reference characters with the addition of the prefix "2."

As seen in Figure 5 and in accordance with one of the herein described methods, the base material 209 may be folded upon itself in a clockwise direction as seen in said figure, to form the bight 220, the edge 221 contacting the rear surface portion thereof of the rear surface 240. The distance from the bight 220 to the edge 221 is preferably sufficient to produce an adequately sized heading 215 and also a rod carrying passage 214. The heading 215 and the passage 214

may then be formed by installing the rows of stitches 222, 206. This operation may be efficiently performed by the use of a hemmer and two needle sewing machine (not shown). Continuous operation or as a separate operation the bights 219 and 208 may be formed, the former by a counter clockwise bending or folding as viewed in Figure 5 and the latter by a clockwise folding as viewed in said figure. Next the row 207 of stitches is installed and these stitches penetrate the portion 227 the bight 208 and the portion 205 of the body 212.

After the folding and stitching operations, just described, have been completed, the portion 204 is folded upon itself in counter clockwise direction as viewed in Figure 5 and may be pressed. When a rod is passed through the passage 214 and the curtain 210 thereby suspended, the parts will substantially take the position shown in Figure 4 in which the valance 213 falls forward to cover the forward portions of the row of stitches 207.

As in connection with the prior described embodiment the forward or front surfaces 230 of the material 209 are exposed toward the inside of the room or toward the front of the curtain, from which the valance 213 projects.

Turning now to the third embodiment of the invention illustrated in Figure 6 parts corresponding to those of the first embodiment are given the same reference characters with the addition of the prefix "3." In this form of the invention a combined valance, heading, and rod tunnel forming strip 350 is folded upon itself adjacent the free edges 351 and 352 thereof to form the bights 320 and 319. The edge 351 is placed inwardly of the upper edge 321 of the body 312 and the upper row of stitches 322 simultaneously forms the heading 315 and the upper portion of the rod tunnel 314. The stitches 322 penetrate the portions 324, 325 and 327.

The edge 352 and particularly the portion 353 is placed in contact with the portion 354 of the body panel 312 and the lower row of stitches 325 is passed through the portions 353, 354 and 326. This last mentioned row of stitches forms the upper limit of the valance 313 and secures the same to the body 312 of the curtain 310, and said stitches also define the lower limit of the rod passage 314. The upper portion 360 of the panel 312 forms the rear portion of the rod passage 314.

It may thus be seen in connection with this embodiment that the valance and heading are readily formed from the single strip 350 and that the outer surfaces 330 of the cloth 309 of which the device 310 is composed are at all times exposed toward the front of the curtain or toward the inside of the room as the case may be.

Where desired the portions 380 and 390 of the strip 350 may be omitted so that the heading 315 and the valance 313 are of a single thickness. Further, if desired the bights 320 and 319 may be retained and may be secured in a lapped condition by suitable hems adjoining said bights, said hems not being shown, but being of a well known type. Similarly additional decorative edging may be applied to the upper and lower edges respectively of the heading and valance, at the positions of the folds 320 and 319.

It may thus be seen that I have disclosed novel and useful curtain constructions and methods of making the same whereby valance and

headed effects are obtained with a minimum of parts and labor. The unitary curtain constructions disclosed provide the appearance given by a curtain with a separately hung and fabricated valance. The advantage inherent in the present constructions lies in the fact that the valance and the curtain being one integral or integrated unit, laundering and pressing operations are greatly simplified.

As will readily be understood, by those skilled in the art to which the present invention relates, a considerable advantage is secured not only in first cost, but also in installation and maintenance expense. With the present invention only a single supporting rod or other comparable means need be used in order to support both the curtain structure and that portion thereof constituting the heading and valance. Furthermore, even though the valance and the curtain are supported from a single rod, a natural and desirable draped effect is formed in each of these parts, and the longitudinal or vertically disposed corrugations constituting the draped effect are independently formed in both the curtain and the valance portion so that the appearance is given of two separate pieces of material hung from two separate supporting rods.

I wish it to be understood that I do not desire to be limited to the exact details of construction shown and described, for obvious modifications will occur to a person skilled in the art.

I claim:

1. A curtain including an integral heading, rod carrying passage, and valance, said curtain comprising a substantially flexible base fabric extending upwardly and folded upon itself to form a first bight, said fabric extending downwardly from said bight a substantial distance and then being folded upon itself upwardly to form a second bight which constitutes the lower edge of said valance; said fabric continuing upwardly to the general location of the first bight and being folded upon itself to form a third bight surrounding the first bight; said base material being again folded upon itself to form a fourth bight and continuing upwardly therefrom to be again folded upon itself to form a fifth bight constituting

the upper edge of said heading; said material continuing downwardly to the location of the fourth bight; means below the fifth bight and above the fourth bight connecting the fabric plies and forming the upper portion of said rod carrying passage; and second means interconnecting the upper edge of the fabric the fourth bight and a portion of the first bight.

2. A curtain including an integral heading, rod carrying passage, and valance, said curtain comprising a substantially flexible base fabric extending upwardly and folded upon itself to form a first bight, said fabric extending downwardly from said bight a substantial distance and then being folded upon itself upwardly to form a second bight which constitutes the lower edge of said valance; said fabric continuing upwardly to the general location of the first bight and being folded upon itself to form a third bight surrounding the first bight; said base material being again folded upon itself to form a fourth bight and continuing upwardly therefrom to be again folded upon itself to form a fifth bight constituting the upper edge of said heading; said material continuing downwardly to the location of the fourth bight; means below the fifth bight and above the fourth bight connecting the fabric plies and forming the upper portion of said rod carrying passage and also the lower portion of said rod carrying passage and second means interconnecting the upper edge of the fabric the fourth bight and a portion of the first bight.

MAURICE DRUCK.
